UNITED STATES PATENT OFFICE.

HERBERT C. WIRT, OF SCHENECTADY, NEW YORK, ASSIGNOR TO THE GENERAL ELECTRIC COMPANY, OF NEW YORK.

DESIGN FOR A LIGHTNING-ARRESTER.

SPECIFICATION forming part of Design No. 29,370, dated September 20, 1898.

Application filed August 29, 1898. Serial No. 689,807. Term of patent 14 years.

To all whom it may concern:

Be it known that I, HERBERT C. WIRT, a citizen of the United States, residing at Schenectady, in the county of Schenectady, State 5 of New York, have invented and produced a new and original Design for a Lightning-Arrester, (Case No. 933,) of which the following is a specification.

In the accompanying drawing, which shows 10 an embodiment of my invention, I have shown a perspective view of a lightning-arrester.

The leading feature of the design consists 15 in the arrangement and configuration of the parts, as shown.

15 Referring by letter to the drawing, A represents a rectangular insulating base or support, which is chamfered on the edges, as indicated at B. Holes C are provided on the corners for the reception of screws or other 20 devices for mounting the support in place.

Mounted on the front of the support are two cylindrical bodies D D', of resistance material, which are adapted to limit the flow of 25 dynamo-current after a lightning discharge takes place. As the bodies of resistance are mounted in similar supports, a description of one of them will be sufficient.

On the upper end of the resistance is a sup-

porting-clip E, which is extended upward at E' to form a terminal to which an electric 30 conductor may be connected. At the lower end of the resistance D is located a clip F, which is extended at F' to form a support for the large metal cylinder G. This cylinder is secured in place by a screw or other device 35 G'. Situated directly below this cylinder and in line therewith is a second metal cylinder H, which is separated from the first by a slight air-space I. Situated at the lower end of the support between the cylinders H 40 and separated therefrom by air-spaces is a metal cylinder J, which is secured in place in any suitable manner, in the present instance a screw K being employed. The cylinder J is carried by a metal support L, which 45 is extended downwardly to form a terminal to which the line or earth may be connected.

What I claim is—

The design for a lightning-arrester, substantially as shown and described. 50

In witness whereof I have hereunto set my hand this 24th day of August, 1898.

HERBERT C. WIRT.
